UNITED STATES PATENT OFFICE

THOMAS J. OWEN, OF AKRON, OHIO

REENFORCED-CONCRETE SLAB

Application filed December 27, 1928. Serial No. 328,730.

This invention, which relates to reenforced concrete building structures, has for its object to provide an improved slab of light and strong construction adapted for floors or 5 roofs and more particularly the latter.

Of the accompanying drawings, Fig. 1 is an elevation, partly in section, showing a portion of a sloping roof structure embodying slabs constructed according to my invention.

Fig. 2 is an end view of one of the slabs on a larger scale.

Fig. 3 is a reverse plan view showing a portion on one of the slabs, partly in horizontal section.

My improved slab may be used in horizontal floors or roofs or in sloping roofs, and in Fig. 1 I have shown a portion of a sloping roof having a frame-work including rafter beams such as 10 and metallic I-beams or purlins 11 placed crosswise thereof to support the several roof slabs 12 which are placed with their side edges adjacent across the spaces between the beams 11 to form a substantially continuous sheet structure. The individual slabs are of greater length than breadth and may be of any suitable dimensions, for example, 5 feet long by 1½ feet wide and 2 inches in overall depth.

The slab 12 is formed with a top web 13 and a plurality, three in this instance, of parallel, longitudinal ribs 14 integral with said web and of substantially uniform depth throughout their length, these ribs projecting below the web 13 preferably to a somewhat greater distance than the thickness of the web. The ends of the ribs are longitudinally recessed at 15 for less than their full depth to form ledges or seats 16 for resting on the I-beams 11, and shoulders 17 to abut against the flanges of said beams for holding the slab against longitudinal displacement. The upper edges of the slab at the ends thereof may further be formed with shallow ledges 18 as an incident to the particular form of mold employed in casting the slab, but these ledges are not an essential structural feature.

Embedded longitudinally in the slab 12, respectively coincident with the several ribs 14, are a series of metallic reenforcing rods or

bars 19 preferably of the twisted, ribbed type and preferably having their extremities 20 turned or hooked at right-angles in the plane of the slab to afford anchorage in the concrete for said rods from the very ends of the rods, which ends extend into the end portions of the slab over the seating faces 16 of the ribs. These rods are positioned in the concrete at depths varying throughout the length of the slab from a minimum at the ends to a maximum in the middle, and are given substantially a catenary or funicular curve by bending from an original straight condition down into the concrete during the formation of the slab so they will constitute tension truss members while leaving the rods covered with a sufficient thickness of concrete to comply with building regulations.

The concrete body may be made with the usual proportions of Portland cement and coarse and fine mineral aggregate, and for the latter I prefer to employ a light and somewhat porous, artificial stone such as the material known as "Haydite" or its equivalent, this being a relatively light and strong, sintered, stone-like, clay product about 8 to 9% of which will float when placed in water so that the collective specific gravity of such material but slightly exceeds that of water. This aggregate may be employed in grades having the particle size respectively of gravel and sand, and its use in this connection, together with the structural features described, affords an exceptionally light and strong reenforced slab peculiarly suited for roofing purposes, the necessary strength factor being obtained with the minimum amount of reenforcing metal and at a relatively low cost.

It will be noted that by notching the ends of the ribs 14 for less than their full depth to form supporting seats, the supports for the ends of the slab are concentrated under the ends of the reenforcing bars 19, expansion and contraction at varying temperatures are allowed in all directions, and an even, collective top surface is provided by reducing the opportunity for irregularities between the seating surfaces and the supporting beams.

A roof thus constructed may be finished with the usual bituminous or other suitable

coating overlying the slabs and covering their intervening joints.

While I have described a preferred embodiment of my invention, it will be understood that the details may be more or less varied within the scope of the appended claims.

I claim:

1. A building slab of elongated form comprising a concrete body including a top web 10 having a series of longitudinal ribs formed on its lower side and extended into the ends to form seating portions, and a series of metallic, tension truss bars embedded in said ribs and having twisted-rib portions extending 15 into the concrete seating portions at the ends of the slab.
2. A building slab of elongated form comprising a concrete body including a top web having a series of longitudinal ribs formed 20 on its lower side and extended into the ends to form seating portions, and a series of metallic, reenforcing truss bars embedded in said ribs substantially in catenary curves and extending into the end seating portions of the 25 slab.
3. A building slab comprising a concrete body including a top web having a series of ribs formed on its lower side and recessed at their ends for less than the full depth of the 30 ribs to form a plurality of seating surfaces, and metallic reenforcing elements embedded in the slab coincident with the ribs and extending into the seating portions of said ribs.
4. A building slab comprising a concrete body including a top web having a series of ribs formed on its lower side and recessed at their ends for less than the full depth of the 35 ribs to form a plurality of seating surfaces at each end of the slab, and a series of metallic, twisted, ribbed, truss bars embedded in said ribs and extending into the seating portions thereof.
5. A building slab comprising an elongated 45 concrete body including a top web having a series of longitudinal ribs formed on its lower side, and a series of metallic truss bars embedded in said ribs and extending into the seating portions at the ends of the slab, 50 said bars having anchoring extremities bent at an angle in the plane of the slab.
6. A building slab comprising an elongated concrete body including a top web having a series of longitudinal ribs formed on its lower 55 side and recessed at their ends for less than the full depth of the ribs to form a plurality of seating surfaces at each end of the slab, said ribs being of substantially uniform depth throughout their length except at the ends, 60 and a series of metallic, twisted, ribbed, truss bars embedded substantially in catenary curves in said ribs and having anchoring extremities bent at an angle in the plane of the slab over said seating surfaces.
- 65 7. A building slab comprising a concrete

body including a top web and a series of ribs formed on the lower side thereof and recessed at their ends to provide seating surfaces, and reenforcing bars located substantially wholly within said ribs and extended into their ends 70 over said seating surfaces.

In witness whereof I have hereunto set my hand this 22d day of December, 1928.

THOMAS J. OWEN.
